CLAIM

The ornamental design for an plate for a firearm, as shown and described.

DESCRIPTION

FIG. 1 is a front perspective view of an plate for a firearm showing our new design;

FIG. 2 is a side view thereof;

FIG. 3 is an opposite side view thereof;

FIG. 4 is a front view thereof;

FIG. 5 is a rear view thereof;

FIG. 6 is a top view thereof; and,

FIG. 7 is a bottom view thereof.

The broken lines immediately adjacent to the shaded area represent unclaimed boundaries of the design. All other broken lines showing the remainder of the plate for a firearm represent unclaimed subject matter. All broken lines form no part of the claimed design.

1 Claim, 5 Drawing Sheets(56)
